UNITED STATES PATENT OFFICE

JOHN P. MCWILLIAMS, OF CLEVELAND, OHIO, ASSIGNOR TO YOUNGSTOWN STEEL DOOR COMPANY, OF CLEVELAND, OHIO, A CORPORATION OF OHIO

SLIDABLE DOOR

Application filed April 15, 1927. Serial No. 183,929.

This invention relates to improvements in slidable doors and more particularly slidable doors for railway cars.

In the use of railway box cars, the railroads 5 are now almost universally requiring the provision of spark and weather seal means along the rear edge of the slidable box car doors. Furthermore, there is a gradually increasing 10 use of steel doors. Heretofore, considerable difficulty has been encountered in providing 15 a satisfactory weather sealing strip on the rear edge of the door, this difficulty being perhaps more accentuated in connection with steel doors than wood doors. It has been customary to provide a strip of more or less 20 angular cross section riveted to the rear edge of the steel door. Due to the fact that the slidable door must slide in a plane closely adjacent the outer surfaces of the posts defining 25 the door opening with only a slight clearance tolerance, it has been necessary in attaching such weather strips to the door to countersink the rivets at the point of attachment in order that there may be no protrusions or 30 obstructions to the sliding of the door past the rear door post of the car. With such constructions, it is obvious that the flush rivets do not provide as rigid a connection as is desirable. In moving the door to closed 35 position, very frequently sledges or claw bars are employed against the rear edge of the door, which causes the latter to be distorted and bent and to exert a turning force on the usually applied weather strip with the result 40 that the attaching rivets are frequently pulled out from the body portion of the door, necessitating serious repairs to the door.

Furthermore, it has been the general custom to utilize the weather strip applied to 45 the rear edge of the door as the rearmost portion of the door and consequently the element which directly received the blows and abuse from the sledging or prying that takes place in trying to force the door to closed position. 50 This same member is also subject to the bumps and injuries resulting from the door being moved to its open position where the rear edge of the door is forced against the usual stops.

55 One object of my invention is to provide

an improved slidable door, and more particularly such a door for railway cars of the box type, the improvements being directed more especially to the provision of an efficient, durable and economical rear edge for the door 55 that will effectively resist distortion, bending or other injury.

A still further object of my invention is to provide a door having the characteristics indicated in the preceding paragraph with especial reference to doors of the so-called "steel or all-metal" type. 60

Another object of my invention is to provide a door with a weather seal strip along an edge thereof so arranged that the same 65 may be attached to the main body portion of the door by the ordinary double-headed rivets so located that the heads of the rivets will in no wise interfere with or in fact, come opposite any portion of the rear door post to the 70 end that the door may be kept in a plane closely adjacent the face of the door post and within the tolerance limits permitted by the railroads.

Another object of my invention is to provide an improved door having a weather sealing strip along the rear edge thereof in combination with an efficient buffer member along the rear edge which will effectively serve not only to prevent distortion of or injury to the 75 weather sealing strip proper, but which will additionally provide a reinforcement to the rear edge of the door serving to prevent bending or distortion thereof. 80

Other objects of the invention such as the 85 lowering of manufacturing costs and wider range of utility of a door of given size will more clearly appear from the description and claims hereinafter following.

In the drawing forming a part of this specification, Figure 1 is a side elevational view of a portion of a box car showing my improved door applied thereto. In this figure, the parts are broken away in order to better accommodate the view on the sheet. Figure 90 2 is an enlarged horizontal sectional view corresponding to the line 2-2 of Figure 1, the parts in this figure also being broken away 95 in order to better accommodate the showing on the sheet. And Figures 3 and 4 are de- 100

tail, horizontal sectional views of modified forms of the rear edge constructions of doors embodying my improvements.

Referring first to the construction illustrated in Figures 1 and 2, the door, as an entirety, is designated generally by the reference character A. The same is illustrated as of the top hung type and is provided with hanger brackets 10—10 carrying rollers 11, which ride upon a suitable track 12 mounted on the side of car above the door opening. In Figure 2 is illustrated a common arrangement of car structure for defining a side door opening and, as shown, the front door post is indicated at 13 and the rear door post at 14, each of said posts being in the form of a Z-bar, the inner flange of which is secured to the side wall structure 15 of the car body. As customary, filler blocks 16 are secured to the door posts in the manner illustrated in the drawing. The front door post 13 is provided with a front weather seal in the form of an angle 17 secured to the post 13 and having the narrow flange 18 thereof parallel with and spaced from the outermost flange of the Z-bar so as to provide a stop and a recess to receive the front edge of the door. The rear door post 14 is illustrated as provided with a well-known form of guard or spark strip 19, the latter comprising a member of somewhat angular cross section with a flange 20 thereof secured to the Z-bar post 14 and with the other flange thereof bent back upon itself and inclined forwardly and inwardly as indicated at 21.

The door which I have chosen for illustrative purposes is of the sheet metal type and preferably has the main body portion thereof comprised of a plurality of panels 22—22 with their horizontal edges overlapped and riveted, the sheet metal of the door being provided with outwardly extended vertical edge corrugations 23 and 24 and upper and lower edge corrugations 25 and 26. Said corrugations are located parallel to and near the respective edges of the door in a well-known manner. The panels are also preferably provided with horizontally extending bracing corrugations 27 which merge, at their ends, with the vertical edge corrugations 23 and 24. To further strengthen the door, bridging strips 28 and 29 are applied to the inner face of the main panel sheets over the front and rear edge corrugations 23 and 24 respectively, as clearly shown in Figure 2. The front bridging strip 28 is preferably doubled back upon itself as indicated at 28^a so as to enclose the forward marginal edge of the panel sheets, it being understood that the said bridging strips will be riveted or spot-welded to the main panel sheets in a well-known manner. It will further be understood that similar bridging strips are applied to the inner face of the door over the top and bottom edge corrugations 25 and 26 but I do not deem it

necessary to illustrate the same for the purposes of this application. While I have illustrated and described a specific form of door proper, it will be understood that my invention is not in any wise confined to the specific construction illustrated.

Referring now more particularly to the rear edge construction of the door, I have provided what may be termed a weather strip designated generally by the reference character B and a buffing member or strip designated generally by the reference character C.

The weather strip B, as illustrated in the form shown in Figures 1 and 2 extends preferably vertically throughout the length of the rear edge of the door and has a flat section 30 lying against and parallel with the flat marginal rear edge portion of the door proper. Forwardly of the flat section 30, the strip B is inwardly offset as indicated at 31 and thence is provided with a forwardly and inwardly extended flange 32 adapted to engage and co-operate with the flange 21 of the guard strip 19 so as to form, with the latter, an efficient spark and weather seal for the door.

The buffer member C, as shown, preferably consists of an angle bar with a flange 33 overlying the outer side of the rear edge marginal portion of the door proper and another flange 34 extending inwardly at substantially right angles and across the end edges of the weather strip B and edges of the bridging strip 29 and of the door sheets proper.

In carrying out my invention, I make the door proper of more than the customary width so that the rear marginal portion of the door will be to the right of the rear door post and any guard strip that may be attached thereto or formed therewith. With this arrangement, I am enabled to provide a section for attaching the weather strip B and the buffer member C in a line to the door proper, which is always disposed rearwardly of the rear door post. This, in turn, permits the use of attaching rivets 35—35, which pass through the flange 30 of the weather strip and the flange 33 of the buffer member so that not only may the outer ends of the rivets be headed, but likewise the inner ends of the rivets as clearly shown in the drawing. The inner ends of the rivets as clearly shown therefore never pass in front of the rear door post and consequently the tolerance limits may be observed with respect to the door and door post.

Numerous advantages result from this novel arrangement at the rear edge of the door. In the first place, a much stronger union or attachment is provided by the double headed rivets as compared with the counter-sunk rivets heretofore commonly used. In the second place, I am enabled to extend the flange 30 of the weather strip B so as to abut the same against the flange 34 of the buffer member. Consequently, when blows or force is applied to the buffer mem-

ber C, the rivets 35 are thereby placed in double shear thus multiplying the effective resistance to tearing out several times over the former methods employed. Again, by 5 utilizing a separate buffer member C, I effectively protect the weather strip B and even though the buffer member may become somewhat distorted due to sledging or prying, the weather strip B retains its normal 10 and proper position to co-operate with the guard strip 19. A still further advantage of my improvements will be noted in that, when the weather strip B and buffer member C are considered collectively, it will be noted 15 that I provide, in effect, a bracing structure for the rear edge of the door on the inner face thereof which is of U or channel shaped cross section with the web of such section (constituted by the flange 30) parallel to and 20 secured against the marginal portion of the door proper. This very effectively braces the door against bending out of a vertical plane and at a point which has heretofore been a point of weakness in most types of steel doors 25 particularly.

A still further advantage is obtained with my improvements resulting from the making of the door somewhat wider than heretofore customary and of a width exceeding the span 30 between the front and rear portions of the two door posts. By doing this, a door of a predetermined width may be utilized for door openings of variable widths between the maximum for which the door is designed 35 and reasonably smaller door openings without necessitating any change in the dies required in manufacturing the door and for impressing the corrugations therein. This result follows from the fact that the weather 40 strip B may be attached as shown in the drawing and by varying the width of the sealing flange 32 thereof and extending it to the desired distance from the line of rivet attachments it can be made to co-operate with 45 guard strips or spark sealing flanges disposed at varying distances from the line of rivets of the door when the door is in closed position. As will be obvious to those skilled in the art, this advantage is of material importance in the production costs of the door. 50 Another advantage from a manufacturing standpoint over prior constructions results from the fact that both ends of the attaching rivets 35 are readily accessible to the rivet heading tools whereas, heretofore, the inner ends of the flush rivets have been in 55 a position making it very difficult for the riveting tool to engage.

Referring now to the construction illustrated in Figure 3, the door body proper 60 may be of the same type throughout as that illustrated in Figures 1 and 2 and heretofore described, it being deemed necessary to illustrate only the rear edge construction and 65 the associated parts on the rear door post.

In the modification of Figure 3, 124 indicates the rear vertical edge corrugation, 129 the corresponding bridging strip, 114 the rear door post and 119 the guard strip secured thereto, said guard strip having a sealing 70 flange 121. The weather strip in this instance is shown in the form of a Z-bar B', one flange of which lies against and is secured to the flat multiple marginal portion of the door. The other flange 132 of the weather strip is inwardly offset and forwardly extended so as to overlie and engage with the flange 131 of the guard strip 119 as illustrated, the two flanges 130 and 132 of the weather strip being united by the intermediate web section 131. The buffer member C' is substantially the same as that illustrated in the modification previously described and it, together with the weather strip B' is secured to the door by a series of rivets 135 headed at both ends and related to the remaining parts of the door and rear door post in the same way as previously described.

In the modification illustrated in Figure 4, the main body portion of the door is illustrated of the same type, the rear vertical edge corrugation being referenced 224, the corresponding bridging strip 229, the door post 214 and the guard strip 219. The guard strip, in this instance, is of ordinary angular cross-section with a flange 221 extending rearwardly and in a plane approximately flush with the outer flange of the post 214. A weather strip B'' and a buffer member C'' are applied to the flat marginal multiple edge of the door in the same way as previously described in connection with the form shown in Figures 1 and 2.

As will be apparent, the same advantages obtain in both of the modifications shown in Figures 3 and 4 as in the form illustrated in Figures 1 and 2 and more specifically heretofore set forth.

I have described my improvements as specifically applied to a slideable box car door of the sheet metal type, but it will be obvious that most of the advantages of my improvements will be equally applicable to wooden doors and also to various other types of metal doors other than the specific type shown in the drawing. All modifications and variations are contemplated that come within the scope of the claims appended hereto.

I claim:

1. A slideable car door comprising: a main body portion consisting principally of a single thickness of sheet metal having a vertical corrugation adjacent the rear edge thereof, with a flat marginal portion between the corrugation and the rear edge proper; a bridging strip secured to said main body portion and extending over said corrugation and rearwardly to the rear edge of the main body 125 130 135

- portion; a weather seal strip secured to the inner face of the two-ply rear edge of the main body portion, said strip having at its front edge a forwardly extending section inwardly offset from the plane of the door
- 5 adapted to co-operate with a weather sealing strip on a door post; and a buffer member, the latter comprising a flange extending inwardly of and abutting the rear edge of said weather sealing strip, and another flange overlying the flat marginal rear edge of the door proper and extending substantially to the adjacent portion of the corrugation, said four elements being secured by a series of rivets common thereto.
- 10 2. A horizontally slidable car door comprised principally of sheet metal and having a flat marginal portion along its vertical rear edge; a sealing strip along said rear edge having a flat flange section lying against the inner face of said flat marginal portion of the door proper and another section extending forwardly and inwardly offset to cooperate with a sealing member carried by the car
- 15 body; a bracing buffer strip along said rear edge having a flange section lying against the outer face of said flat marginal portion of the door proper and another flange section projecting inwardly across the edges of said flat
- 20 marginal portion and rear edge of the sealing strip flange section whereby the sealing strip is protected against direct access by a tool or the like; and a series of rivets extending through said flat marginal portion of the
- 25 door proper and said overlapped flange sections of the two strips.
- 30 3. A horizontally slidable car door comprised principally of sheet metal and having a flat marginal portion along its vertical rear edge; a sealing strip along said rear edge having a flat flange section lying against the inner face of said flat marginal portion of the door proper and another section extending forwardly and inwardly offset to cooperate with a sealing member carried by the car
- 35 body; a bracing buffer strip along said rear edge having a flange section lying against the outer face of said flat marginal portion of the door proper and another flange section
- 40 projecting inwardly across the edges of said flat marginal portion and rear edge of the sealing strip flange section; and a series of rivets extending through said flat marginal portion of the door proper and said overlapped flange sections of the two strips, said
- 45 inwardly extending flange section of the buffer strip abutting the rear edge of the sealing flange section whereby said rivets are placed under double shear when force is applied
- 50 to the buffer strip edgewise of and toward the door.
- 55 In witness that I claim the foregoing I have hereunto subscribed my name this 13th day of April, 1927.
- 60
